(57) **CLAIM**

The ornamental design for a tool holder, as shown and described.

DESCRIPTION

FIG. 1 is an isometric view of the tool holder assembled with a fence component and an adjuster component;

FIG. 2 is an isometric view of the tool holder of FIG. 1;

FIG. 3 is a front view of the tool holder of FIG. 1;

FIG. 4 is a rear view of the tool holder of FIG. 1;

FIG. 5 is a right side view of the tool holder of FIG. 1;

FIG. 6 is a left side view of the tool holder of FIG. 1;

FIG. 7 is a top view of the tool holder of FIG. 1; and,

FIG. 8 is a bottom view of the tool holder of FIG. 1.

The broken lines in the drawings illustrate an attachment for the tool holder and form no part of the claimed design.
